United States Patent Office

Des. 181,105
Patented Oct. 1, 1957

181,105

ELECTRIC SHAVER

Roger I. Protas, Pittsburgh, Pa., assignor to Schick
Incorporated, Lancaster, Pa., a corporation of Delaware

Application March 19, 1957, Serial No. 45,317

Term of patent 14 years

(Cl. D22—3)

Fig. 1.

Fig. 2.

Fig. 3.

Fig. 4.

Fig. 1 is a front elevation of an electric shaver embodying my new design (the rear elevation being the same in appearance);

Fig. 2 is a side elevation;

Fig. 3 is a top plan view; and

Fig. 4 is a bottom plan view thereof.

I claim:

The ornamental design for an electric shaver, substantially as shown and described.
